UNITED STATES PATENT OFFICE.

ARBER TEBBIT, OF MEDINA, OHIO.

CATCHING AND KILLING DEVICE.

No. 913,858.

Specification of Letters Patent.

Patented March 2, 1909.

Application filed March 16, 1908. Serial No. 421,572.

To all whom it may concern:

Be it known that I, ARBER TEBBIT, a citizen of the United States, residing at Medina, in the county of Medina and State of Ohio, 5 have invented certain new and useful Improvements in Catching and Killing Devices, and do declare that the following is a full, clear, and exact description of the invention, which will enable others skilled in the art to 10 which it appertains to make and use the same.

My invention relates to improvements in catching and killing devices, and the invention consists in a device adapted to be supported on a table or stand or on the side wall 15 or ceiling of a room, as may be deemed desirable, as well as to be used for killing flies by striking them when they are lighted, all substantially as shown and described and particularly pointed out in the claims.

In the accompanying drawings, Figure 1 is an edge elevation of the device, and Fig. 2 is a side elevation thereof, Fig. 3 is an edge elevation, partially sectioned, of the wire 25 stems or ribs of the device, and Fig. 4 is a sectional edge elevation of the paper covering therefor. Fig. 5 is a perspective view of a portion of the said wires and means to support the same as hereinafter fully described.

30 The essential idea of this invention is to provide a combination which may be used by hand to kill flies by striking them on the wall wherever they may be lodged, or as an attraction covered with sticky material or 35 object for the flies to lodge upon and be thus caught, or both. If used as an attraction or lodging place for flies the device is adapted to be placed almost anywhere in a room where a smooth surface is found, such as a 40 side wall or a piece of furniture other than a stand or table, and whereon the device may be engaged horizontally or even suspended or supported vertically by hanging the same from the ceiling.

45 To these and other ends, the device consists in a tapered standard or handle H with a flexible or rubber suction or vacuum cup C secured on the end thereof and of such size and strength as to serve as a base or rest for 50 the device on a table, and as an adhering or affixing member which can be pressed against a smooth firm surface and by expelling the air therefrom cause vacuum and obtain engagement by atmospheric action 55 which will support the device in horizontal or other position. A socket c in the top of cup

C serves to engage the cup on the handle and a suitable ring or band 2 about the outside of said socket fixes it in place.

A double sided or two part wire or rib support D is provided with socket or half round engaging portions d locked upon the upper or opposite end of handle H by band or ring 3. Each half of part D is substantially a duplicate of the other half except as 60 to the number of perforations therein for the said wires or ribs, and consists of a light piece of sheet metal stamped into the requisite shape and provided with a line of transverse perforations in which the wires 5 and 6 re- 65 spectively are headed and soldered or otherwise rigidly secured. These wires are in alternate relation to each other corresponding to the alternate disposition of the respective perforations or holes in which they are se- 70 cured in the opposed plates D, and one of said plates has say four holes and wires, Fig. 5, and the other five holes and wires 6, and all wires are of substantially the same length. The said wires are further disposed to form 75 something of a fan shape, the same radiating from their supports and giving an outer spread effect, and have their extremities bent or turned back upon themselves to form loops 8, over which the paper covering or 80 fly-paper P is secured. Said paper is cut to fold across its center and overlap said wires on both sides with its extremities projecting into the space between plates D and wires 5 and 6 therein so as to clamp said extremities 85 in said spaces when the parts are put in place for use.

It is noticed that handle H is tapered and that the socket portions d of plates D are correspondingly tapered, so that when the parts 95 are assembled and secured in place on handle H the ends 10 of paper cover P are clamped fast, as above described. Now, the cover P is made of specially prepared paper struck with embossed perforations of diamond shape 100 in this instance and liberally scattered over the surface thereof and of a size and number to facilitate the use of the device for striking flies. The less resistance by the air the better for this purpose, and said holes come op- 105 posite each other to this end. Again, by striking up the stock outward about said holes I throw up a wall 12 about each hole which produces a corresponding depression between the holes, and said depressions espe- 110 cially are adapted to receive the adhesive or striking coating upon which I depend to

catch the flies when the device is used only as a bait with a sticking medium. I may therefore dip the sheet of paper in such adhesive material or otherwise apply the adhesive and coat the paper therewith, except 5 ends 10. Then in order to use the device for striking flies with the adhesive thereon I seal or otherwise treat the edges of walls 12 so that the adhesive thereon will be deprived of 10 its adhesive quality and not soil a table cloth or wall when struck thereby, but the space between said edges will remain sticky. In this way the flies will be caught if they light 15 therein and flies that are killed by the stroke will be picked up by the adhesive and not allowed to lie dead where they have been struck.

The device is thus shown to have a rigid handle and a flexible striking portion which 20 is of such open work construction as to permit free flow of air through the same and yet has a sticky or adhesive surface serving the double purpose of catching live flies and picking up dead flies. The paper cover can 25 be replaced by simply removing band 3 and releasing the parts confined thereby, and the taper of handle H locks said band or ring.

The wires or ribs 5 and 6 are provided with short spurs 7 at intervals adapted to engage 30 the paper covering and resist any tendency therein to fly or slip off during use.

What I claim is:—

1. A fly catching and killing device having a rigid handle and spring ribs fixed thereon, 35 and an open work paper cover engaged over said spring ribs.

2. A catching and killing device having a rigid handle and a series of independent wire ribs fixed thereon, and a perforated and em- 40 bossed paper cover over both sides of said ribs.

3. A catching and killing device handle and wire ribs radially disposed thereon in substantially fan shape, and an embossed 45 open work paper cover overlapping said

wires upon both sides and coated with a sticky material.

4. A fly catching device having a rigid handle with a tapered shank, a series of spring wire ribs and plates to which said 50 wires are affixed, means securing said plates to the said shank, and an open work cover removably secured over said ribs.

5. A fly catching device having a handle and a two part support removably fixed 55 thereon, wires radially fixed in said support and a paper cover bent back upon itself at its middle and engaged over said wires with its ends secured between the sides of said support.

6. A fly catching device comprising a handle and a two part support fastened on one end thereof, a series of spring wires rigidly fixed in said support alternately to each other and an embossed open work cover 65 over said wires.

7. The device shown having a rigid handle and an exhaust cup on one end, a series of radially disposed spring wires supported from the other end thereof and a sheet of 70 embossed open work paper engaged over said wires.

8. A fly catching and killing device having a series of wire ribs with spurs at intervals and a covering of paper overspreading said 75 wires and in position to be engaged by said spurs.

9. A fly catching and killing device having a skeleton frame of wires and a paper covering therefor provided with openings having 80 raised walls about the same and covered with an adhesive material, and the exposed edges of said walls free of the adhesive.

In testimony whereof I sign this specification in the presence of two witnesses.

ARBER TEBBIT.
